UNITED STATES PATENT OFFICE.

WILLIAM FELSTEAD, OF VICTORIA, BRITISH COLUMBIA, CANADA.

SHOE-HEEL.

1,250,828.

Specification of Letters Patent. Patented Dec. 18, 1917.

Application filed February 24, 1917. Serial No. 150,729.

To all whom it may concern:

Be it known that I, WILLIAM FELSTEAD, a subject of the King of Great Britain, and a resident of Victoria, British Columbia, 5 Dominion of Canada, have invented certain new and useful Improvements in Shoe-Heels, of which the following is a specification.

My invention relates to heels for boots and shoes adapted for substitution, when worn out, in a simple and easy manner not requiring the services of an expert shoe re-pairer, and the main object thereof is to provide such heels which provide a shell of 15 relatively stiff material inclosing a wood, composition, or other filler and extended upwardly around the rear of the shoe upper to support the shoe counter, as well as being forwardly directed to retain the shoe in 20 shape at the sides of the arch of the foot.

My invention is fully described in the following specification, of which the accompanying drawings form a part, in which like characters refer to like parts in each of the 25 views, and in which:—

Figure 1 represents a shoe provided with my improved replaceable heel;

Fig. 2 is a bottom plan view of the heel and part of the shoe;

Fig. 3 is a section taken on the line 3—3 of Fig. 2; and

Fig. 4 is a view of the blank of which the shell is formed;

Fig. 5 is a view of one of the metal stiff- 35 eners.

Referring to the drawings, 5 shows a shoe provided with a detachable heel 6 formed of a shell 7 and a filler 8 of wood, composition, or the like, having a plurality of lengths of 40 metal ribbon 9 bent into looped form and embedded in said filler, the latter also having a plurality of rubber plugs 10 embedded therein to prevent slipping, as on wet pavement.

The shell 7 is formed of a sheet of relatively stiff material, such as metal or leather, struck up from a blank 11 shown in Fig. 4, said blank having a central portion 12 provided with an upwardly extended projection 13 and two end members 14 and 15, said blank being bent on lines 16 and the ends 14 and 15 turned rearwardly and curved

into the form or shape of a heel and secured together in any desired manner, the central portion 12 forming the front of the heel, and 55 the projection 13 being bent forwardly on the line 17 and projected beneath the arch of the shoe.

When the heel is so formed, ears 18 and 19 extend forwardly of the heel at the sides of 60 the shoe and may be held in place by rivets 20, thus adding strength to the sides of the shoe, whereas the members 14 and 15, being extended upwardly around the rear of the shoe, add to the strength of the counter and 65 prevent the same from being run over.

The projection 13 has an inverted V-shaped tongue 21 cut therefrom and adapted to be bent rearwardly, as shown in Fig. 3, whereas the end members 14 and 15 have 70 each a plurality of such tongues 22 cut therefrom and bent inwardly to hold the filler in place and, when the heel is attached to a shoe by means of nails 23 and a suitable waterproofing introduced between the heel and 75 shoe, the latter is as good as new so far as the heel is concerned and the shank is supported by the projection 13 while the counter is protected by the shell 7 against wear as well as against treading over. 80

The shell is reinforced at its front corners by vertical metal stiffeners 24 constructed as shown in Fig. 5, and these stiffeners are secured by rivets 25.

Having fully described my invention, what 85 I claim as new, and desire to secure by Letters Patent, is:—

1. A shoe heel, consisting of a shell formed of a member having a middle and end portions adapted to embrace the front and the 90 sides and back of the heel, respectively, each of such portions having extensions at their upper edges, the extension of the middle portion projecting forwardly to engage under the arch of the shoe and the extensions of 95 the end portions projecting to engage the sides of the counter of the shoe and said shell having engaging elements projecting inwardly from its inclosing walls, and a filler disposed within the shell. 100

2. A shoe heel, comprising a shell of stiff material having inwardly directed integral tongues thereon, a filler of relatively light material in said shell and held by said

tongues, a shank supporting member extended forwardly from said shell, said shell being extended upwardly to support the counter of a shoe, and metal reinforces arranged on the inner surface of the shell at the front corners of the heel.

3. A blank for forming a heel shell, hav-

ing a central member provided with a projection having a tongue struck up therefrom, and end members provided with tongues struck up therefrom, said end members being of greater width than the central member and having ears at their inner ends.

WILLIAM FELSTEAD.
